(57) **CLAIM**

We claim the ornamental design for the optoelectronic sensors, as shown.

DESCRIPTION

FIG. 1 is a left view of a first embodiment of the optoelectronic sensors;

FIG. 2 is a front view of a first embodiment of the optoelectronic sensors;

FIG. 3 is a right view of a first embodiment of the optoelectronic sensors;

FIG. 4 is a back view of a first embodiment of the optoelectronic sensors;

FIG. 5 is a bottom view of a first embodiment of the optoelectronic sensors;

FIG. 6 is a top view of a first embodiment of the optoelectronic sensors;

FIG. 7 is a perspective view of a first embodiment of the optoelectronic sensors;

FIG. 8 is a left view of a second embodiment of the optoelectronic sensors;

FIG. 9 is a front view of a second embodiment of the optoelectronic sensors;

FIG. 10 is a right view of a second embodiment of the optoelectronic sensors;

FIG. 11 is a back view of a second embodiment of the optoelectronic sensors;

FIG. 12 is a top view of a second embodiment of the optoelectronic sensors;

FIG. 13 is a bottom view of a second embodiment of the optoelectronic sensors;

FIG. 14 is a perspective view of a second embodiment of the optoelectronic sensors;

FIG. 15 is a left view of a third embodiment of the optoelectronic sensors;

FIG. 16 is a front view of a third embodiment of the optoelectronic sensors;

FIG. 17 is a right view of a third embodiment of the optoelectronic sensors;

FIG. 18 is a back view of a third embodiment of the optoelectronic sensors;

FIG. 19 is a bottom view of a third embodiment of the optoelectronic sensors;

FIG. 20 is a top view of a third embodiment of the optoelectronic sensors; and,

FIG. 21 is a perspective view of a third embodiment of the optoelectronic sensors.
